PORTABLE TURKISH OR RUSSIAN STEAM
BATH

Paul Varga, Stamford, Conn.

Application November 24, 1937, Serial No. 176,278

3 Claims. (Cl. 4—164)

This invention relates to new and useful improvements in a portable Turkish or Russian steam bath.

The invention has for an object the construction of a device as mentioned which is characterized by an arrangement by which one may apply steam or hot air to half of one's body, or three-quarters of one's body, or for action upon the whole body.

Still further the invention proposes an arrangement by which it is possible to control the quantity of steam within the bath.

Another object of the invention is to provide a removable rubber canvas or other flexible member, or similar material within the bath which may be utilized in dividing the bath, for the application of steam to various portions of the body, as already specified.

Still further the invention proposes a novel mechanism for producing and controlling the steam.

Another object of the invention is to provide a seat within the bath and to associate this seat with a foot board in a novel manner.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a device constructed according to this invention.

Fig. 2 is a front perspective view of the device with the door open.

Fig. 3 is a front elevational view of the device illustrated with the seat and foot board raised.

Fig. 4 is a horizontal sectional view taken on the line 4—4 of Fig. 3.

Fig. 5 is a horizontal sectional view taken on the line 5—5 of Fig. 2.

Fig. 6 is a fragmentary vertical sectional view taken on the line 6—6 of Fig. 4.

Fig. 7 is a transverse vertical sectional view taken on the line 7—7 of Fig. 3.

Fig. 8 is a rear elevational view of the device.

The portable Turkish and Russian steam bath, according to this invention, comprises a hollow body 10 having a front door 11, a top hingedly mounted panel 12 and an interior compartment 13 of bench height. A seat 14 is mounted on the bench compartment 13. A foot board 15 is provided for the floor of the body 10. A horizontal screen or rubber canvas material 16 is arranged

at the two-thirds elevation within the body 10. A mechanism is also provided within the bench compartment 13 for manufacturing, controlling and supplying steam and hot air as hereinafter more fully described.

The hollow body 10 is of box shape in construction. The door 11 thereof is hingedly supported by the hinges 16. It is provided with a latch 17 which may be manipulated from the inside as well as the outside so that the door may be opened when required. The top panel 12 is supported at one side by the hinges 18. It may be held in various raised positions by an arm structure 19 connected between one of the sides and the top of the hollow body. The cover 12 is formed with a central opening 20 closed by a flexible or other covering element 21. This covering element 21 is formed with an opening 22 through which one's head may be extended. This opening is adapted to be partially closed by fasteners 23 arranged upon the ends thereof. It is thus possible to restrict the opening 22 to fit around one's neck and to prevent the free discharge of steam from within the hollow body.

The seat 14 is pivotally supported at its rear end by a shaft 25 to which the seat is firmly connected. This shaft 25 is supported in bearings 26. One end of the shaft 25 is provided with a pinion 27 engaged by a chain 28. This chain extends downwards and engages a pinion 29 supported on a shaft 30. The shaft 30 is rotatively mounted in bearings 31. One side of the foot board 15 is rigidly attached to the shaft 30. The arrangement is such that the foot board 15 may pivot upwards and downwards along the arc A in Fig. 7. Such pivoting of the foot board will be transmitted to similarly pivot the seat 14, as indicated by the dot and dash lines B.

In its lowered position the seat 14 extends over and covers a steam discharge container 32. This container is connected by a pipe 33 to a control valve 34, which in turn is connected with a boiler 35. The boiler 35 is arranged within the bench compartment 13. Upon the top of the bench compartment 13 there is also a control valve 36, a control switch 37, and a burner switch 38. These devices operate mechanism within the bench compartment, as follows:

The boiler 35 is supported above a kerosene, gas, or other type of heater 39 which is controlled by the control 38. The arrangement is such that the control 38 may be turned one way or the other to increase or decrease the size of the flame from the burner 39. The boiler 35 may also be heated by an auxiliary electric heater 40. This

electric heater 40 is controlled by an electric circuit within a conduit 41. The electric circuit within this conduit is controlled by the electric switch 37. The arrangement is such that the switch 37 may be turned on to render the electric heater operative, or turned off to turn off the heater.

The steam discharge from the boiler 35 is adapted to pass through a pipe 42 which connects with a three-way valve 36. This valve 36 is adapted to be adjusted in one position to send a portion of the steam from the boiler through a pipe 43 which discharges through an opening 44 in the bottom portion of the hollow body 10. Or, the three-way valve 36 may be moved to a position in which it is fully open to discharge the full supply of steam through the opening 44. The third position of the valve 36 is one in which the steam will discharge through a pipe 45 which discharges into a condenser 46 which will condense and so dissipate the steam. This condenser is mounted within the bench compartment 13.

At the bottom of the bench compartment 13 there is a baffle 47 which has several openings 48 through which hot air from within the bench compartment 13 may be discharged. A fan blower, not illustrated on the drawings, may be caused to operate to blow hot air from the interior of the bench compartment through the openings 48 and into the interior of the hollow body 10.

The rubber canvas 16 or similar material, is formed from adjacent sections 16^a and 16^b which are secured together by hockless fasteners 49 upon adjacent sides. These hockless fasteners are controlled by a slide 50. Each of the sections 16^a and 16^b are releasably mounted within the hollow body 10 by a plurality of snap fastener elements 51 or other holding elements connected between the edges thereof and the side walls of the hollow body 10. The arrangement is such that one's body may pass between the sections 16^a and 16^b, and the slide 50 pulled up close to the body so as to confine as much steam as possible below the rubber canvas 16.

The operation of the device is as follows:

One may take a Turkish or Russian bath by entering the hollow body 10 through the door opening and closing the door 11. The seat 14 may be in the lowered position and then the foot board 15 will also be in its lowered position, in which position it is not possible to raise these parts except if one steps out from the hollow body. In the lowered position of these parts, it is possible to control the operation of the supply of steam for the reason that the seat 14 is not as wide as the top of the bench compartment 13.

The control valves and apparatus 34, 38, 36 and 37 are arranged at the sides of the seat 14. These controls may be manipulated to heat water within the boiler 35 and create steam, and the steam may be controlled to discharge into the hollow body. By the proper manipulation of the

controls and the divisional rubber canvas 16 it is possible to take a steam or heat bath along various parts of one's body. Still further, it is possible that the treatment be taken sitting down or standing up, as conditions may warrant. The baths may be adjusted so that persons with various ailments such as rheumatism, high blood pressure, appendicitis, and other disorders may use them.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a portable Turkish or Russian steam bath, 20 a hollow body having a front door, a top hingedly mounted panel, an interior compartment of bench height and a floor area, a seat movably mounted on said interior compartment, a movably mounted foot board for covering the entire 25 floor area of said body, mechanism within said compartment for supplying steam and heat to said hollow body and operated by controls on said interior compartment, and means for holding said seat down over said interior compartment when said foot board is down.

2. In a portable Turkish or Russian steam bath, 30 a hollow body having a front door, a top hingedly mounted panel, an interior compartment of bench height and a floor area, a seat mounted on 35 said interior compartments, a foot board for covering the entire floor area of said body, said seat being pivotally mounted, said foot board being pivotally mounted, and means connecting said seat and foot board in a manner so that when 40 one moves up the other follows, and when one moves down the other follows, whereby when a person is in said bath and the floor board and the seat are down they cannot be raised.

3. In a portable Turkish or Russian steam 45 bath, a hollow body having a front door, a top hingedly mounted panel, an interior compartment of bench height and a floor area, a seat mounted on said interior compartment, a foot board for covering the entire floor area of said 50 body, said seat being pivotally mounted, said foot board being pivotally mounted, and means connecting said seat and foot board in a manner so that when one moves up the other follows, and when one moves down the other follows, 55 whereby when a person is in said bath and the floor board and the seat are down they cannot be raised, said connecting means comprising shafts pivotally supporting said foot board and seat, pinions upon said shafts, and a chain 60 mounted between said pinions.

PAUL VARGA.
